(57) **CLAIM**

The ornamental design for a packaging box, as shown and described.

DESCRIPTION

FIG. 1 is a front view of a packaging box according to a first embodiment of our new design;

FIG. 2 is a back view of the packaging box shown in FIG. 1;

FIG. 3 is a left view of the packaging box shown in FIG. 1; FIG. 4 is a right view of the packaging box shown in FIG. 1;

FIG. 5 is a top view of the packaging box shown in FIG. 1; FIG. 6 is a bottom view of the packaging box shown in FIG. 1;

FIG. 7 is a perspective view of the packaging box shown in FIG. 1;

FIG. 8 is a front view of a packaging box according to a second embodiment of our new design;

FIG. 9 is a back view of the packaging box shown in FIG. 8;

FIG. 10 is a left view of the packaging box shown in FIG. 8;

FIG. 11 is a right view of the packaging box shown in FIG. 8;

FIG. 12 is a top view of the packaging box shown in FIG. 8;

FIG. 13 is a bottom view of the packaging box shown in FIG. 8; and,

FIG. 14 is a perspective view of the packaging box shown in FIG. 8.

The broken lines are shown for the purpose of illustrating parts of the article that form no part of the claimed design. The HIKVISION® logo shown in the drawings, and forming part of the claim, is a registered trademark of Hangzhou Hikvision Digital Technology Co., Ltd Corporation.
